COKING RETORT OVEN

Joseph van Ackeren, O'Hara Township, Allegheny County, Pa., assignor to The Koppers Company of Delaware, a corporation of Delaware

Application March 10, 1931, Serial No. 521,406

12 Claims. (Cl. 202—143)

My invention relates to coking retort ovens and particularly to regenerator arrangements.

It is an object of the present invention to provide regenerators that are so arranged and connected as to substantially prevent any leakage between regenerators carrying fuel gas and regenerators carrying waste gases.

It is a further object of my invention to provide fuel gas regenerators that are so isolated from waste gas regenerators by means of air regenerators and passageways in series therewith that counterflow between fuel gas regenerators and waste gas regenerators is substantially prevented.

15 My invention is particularly adapted to be employed in connection with coking retort ovens of the type in which the flame flues of the heating walls are connected at their tops in pairs for operation in series in reverse directions alternately. The flues arranged in this manner are sometimes designated as "hairpin" flues. My invention, however, is not necessarily limited to flame flues of this particular type.

20 In the coke oven of my invention, I may also connect the bottom portions of the members of the respective pairs of flame flues in order that, in either direction of their operation, a portion of the waste gases or gases of combustion may circulate in the flues thus connected for the purpose of diluting the fuel gases and thus elongating the flames of combustion. It will be appreciated that this arrangement of the flues permits the construction of oven chambers of relatively great height since the elongation of the 25 flames of combustion renders the heating of the charge in the oven chambers substantially uniform throughout their height.

An important feature of my present invention is the provision of regenerators beneath the oven 30 chambers and the heating walls that are so arranged and connected as to substantially prevent counterflow between regenerators carrying fuel gas and those carrying waste gases. The regenerators are preferably arranged in groups that 35 are adapted for operation as inflow and outflow regenerators alternately. Each group of regenerators comprises an intermediate regenerator having on one side thereof a second regenerator and on the other side a slot or passageway that is in series with the second regenerator. When a group operates to supply combustible media to the flame flues, the intermediate regenerator carries fuel gas while air flows through the slot and the other regenerator in series. 40

55 This arrangement provides against counterflow

between the fuel gas regenerator and adjacent outflow regenerators carrying waste gases.

In addition to the foregoing arrangement for supplying the flame flues with lean gas and air, rich gas may be supplied through vertical gas guns, the battery being of the underburner type in which the various connections for rich gas are accessible to the operator.

Reference may now be had to the accompanying drawings, in which

Figure 1 is a view in transverse vertical section of a coke-oven battery embodying my invention;

Fig. 2 is a view in longitudinal vertical section of the battery of Fig. 1 and taken on lines C—C and D—D of Fig. 1;

Fig. 3 is a view in horizontal section, taken on line III—III of Fig. 2;

Fig. 4 is a fragmentary view, taken on line IV—IV of Fig. 2;

Fig. 5 is an enlarged detail view in transverse vertical section, taken on line V—V of Fig. 3; and

Fig. 6 is a fragmentary enlarged view taken in vertical section on line VI—VI of Fig. 2.

Referring to the drawings, a coke-oven battery 1 comprises a series of horizontal oven chambers 2, which alternate with heating walls 3 therefor. The battery is provided with a top 4 having charging holes 5 extending therethrough, by means of which the oven chambers 2 may be charged with coal. Beneath the oven chambers 2 and heating walls 3 is horizontal brickwork 6, which separates the oven chambers and heating walls from two rows of crosswise regenerators 7 and 8.

Each row of regenerators extends substantially half the width of the battery. The battery structure is supported upon a foundation comprising a pad 9, pillars 10 and a base 11 which may be of concrete. This arrangement provides 40 passageways for convenient access to the bottom portion of the battery structure.

The regenerators 7 are each provided with a sole flue 12, which is connected through a side wall 13 of the battery to a reversing box 14 for controlling the admission of producer gas to the regenerators or the flow of waste gases therefrom, as the case may be. The regenerators 8 are provided with a communicating flue 15 which connects two regenerators in endwise 50 alignment but does not extend through the side walls 13 of the battery.

The regenerators, with the exception of two at each end of the battery, are preferably arranged in groups. Each group comprises a re-

55

generator 7 having on one side thereof a regenerator 8. On the other side of the regenerator 7 is a narrow slot or passageway 16 extending the entire width of the battery. Each slot 16 may 5 be regarded as in effect two slots, each of which is substantially coextensive in length and in height with the regenerators 7 and 8 and which is connected in series with a regenerator 8.

Each slot 16 is provided with a sole flue 17, 10 the ends of which extend through the respective side walls 13 of the battery, and are provided with the usual reversing boxes 14. Each slot 16 extends through a partition wall 18, which extends longitudinally of the battery for separating the rows of regenerators, and is connected to the regenerators 8 in series therewith by means of a duct 20 within the partition wall 18 and connected to the communicating flue 15 of two regenerators 8 in endwise alinement.

20 Fuel gas, such as producer gas, is supplied for combustion in the heating walls 3 by means of gas mains 22 that are connected through suitable valves 23 to the sole flues 12 of the regenerators 7 in each group. Coke-oven gas, when employed 25 as a fuel, is supplied by a main 24, headers 25 and vertical gas guns 26 that extend between the regenerator groups and through the horizontal brickwork 6. Waste gases or gases of combustion pass through the several sole flues of 30 the outflow regenerators and connected slots 16 and into a waste-gas main 27 on each side of the battery and which may be connected to the usual stack.

As shown in Fig. 1, each heating wall 3 is provided with a series of vertical flame flues 28 that 35 are connected in pairs at their tops by ducts 29 for operation in series. The flues of each pair are also connected at the bottom by a duct 30 in order to permit the recirculation of a portion 40 of the waste gases. The number of the vertical flues may be as desired, fourteen being shown in each heating wall by way of example.

Each of the regenerators 7 and 8 is connected 45 to members of half the pairs of flame flues of two heating walls by means of inclined ducts 31. There is an exception, however, in the case of the two smaller regenerators 32 in each row at each end of the battery in that they are each connected to the flame flues of a single heating 50 wall. Each flame flue 28 is connected to a regenerator 7 and a regenerator 8 or to two regenerators 32, as the case may be.

It may be assumed that the battery 1 is operating 55 with producer gas as a fuel, in which case producer gas is supplied by the gas mains 22 through the reversing boxes 14 to the sole flues 12 of the corresponding inflow regenerators 7 and 32. Air flows through reversing boxes 14 connected to the slots 16 and through the ducts 60 20 to the inflow regenerators 8 in series therewith. Air also flows through one of each pair of regenerators 32 when they operate as inflow regenerators. Combustion occurs in one member 65 of each pair of flame flues in each of the heating walls and gases of combustion pass downwardly in the other member of the pair.

A portion of the waste gases passes through 70 each duct 30 and is recirculated in the flame flue in which combustion occurs while the remaining portion passes out through inclined ducts 31 to the outflow regenerators and their connections to the waste-gas mains 27. The direction of flow of gases in the several regenerators may be as 75 indicated by the upper rows of arrows and legends

in Fig. 2, in which the legends G, A and WG represent fuel gas, air and waste gases, respectively.

During this operation, each fuel gas regenerator 7 has, on one side thereof, an air regenerator 8 and, on the other side thereof, the slot 16, which 5 is in series with the air regenerators. Accordingly, each fuel gas regenerator is substantially enclosed between an air regenerator and a slot for carrying air whereby counterflow between fuel gas regenerators and waste-gas regenerators 10 is effectually prevented.

When the operation of the battery is reversed, as occurs periodically, the inflow regenerators become outflow regenerators and waste gases 15 traverse the regenerators, together with the slot 16, in series with one of them. In a similar manner, the groups of outflow regenerators and connected slots become inflow regenerators and operate in the manner described above.

The directions of flow are now those indicated 20 by the lower rows of arrows and legends in Fig. 2. The inflow regenerators have the same relations as those described above for the previous reversal period.

As clearly shown in Fig. 2, expansion joints 34 25 extend downwardly from the bottoms of the oven chambers 2 and are connected to the tops of the slots 16. The expansion joints 34 also extend from the bottoms of the sole flues 17 to the 30 bottom of the battery. The expansion joints are 35 filled with rock wool. The foregoing arrangement permits the necessary relative movement but tends to prevent any leakage along the joints by reason of pressure differentials between various parts to which the joints are connected.

The arrangement of the regenerators and their 40 connections in the manner described above possesses several advantages. It is highly important to prevent leakage between fuel gas regenerators and this is accomplished by placing air spaces, 45 one of which may be a regenerator on opposite sides of the fuel gas regenerators.

The slot or passageway that is in series with 50 certain of the regenerators provides means for 45 additionally preheating air by reason of its relatively long path through the battery structure before it is received by the communicating flue for the air regenerators. The slots may be relatively narrow and, accordingly, occupy relatively little space.

The slots which extend transversely of the battery and parallel with the oven chambers and 55 heating walls afford a convenient means for connecting the expansion joints that are connected to the bottoms of the oven chambers. This arrangement insures that any leakage that might occur either along the expansion joints or through the walls in which the slots are located would not cause any mixture of fuel gas and waste gases.

While a relatively few oven chambers and heating walls have been shown and described, it will be appreciated that their number may be such as desired without departing from the principles of construction and operation of the coke oven of 60 my invention.

I claim as my invention:

1. Coke-oven structure comprising a series of combustion heating flues therefor and regenerators communicating therewith, said regenerators 70 being arranged side-by-side in a horizontal row and in side-by-side groups adapted to operate for inflow of combustion media and concurrent outflow of waste gas in alternation with each other, each group comprising two regenerators side-by- 75

side communicably connected to the same flue for simultaneous delivery of a gas to the same flame flue and a passageway on one side of the group and substantially co-extensive with the regenerator contiguous thereto in the group in length and in height and communicating in series with the other regenerator of the group in the order, passageway, regenerator, combustion flue, the passageways of each of said groups being interposed between adjacent regenerators of contiguous groups of regenerators.

2. Coke-oven structure comprising a series of combustion heating flues therefor and regenerators communicating therewith, said regenerators being arranged side-by-side in a horizontal row and in side-by-side groups each group being composed of two regenerators side-by-side and a passageway on one side of the group and substantially co-extensive with the regenerator contiguous thereto in the group and in length and height, said passageway communicating with the other regenerator of the group for flow in series with the combustion flues in the order—passageway, regenerator, combustion flue—, one of said groups being adapted for supply of air through said passageway and the regenerator in series therewith and fuel gas simultaneously through the other regenerator to the combustion flues communicating therewith while another group at the other side of the passageway concurrently conveys waste gases from combustion flues.

3. Coking retort oven structure comprising a series of combustion heating flues therefor and means for supplying fuel gas and air thereto and for concurrently conducting waste gases therefrom, said means comprising side-by-side regenerators communicating with said combustion flues and in groups that are arranged side-by-side for simultaneous inflow of fuel gas and air and outflow of waste gas with a regenerator for fuel gas in each group next to a next adjacent group of regenerators, and passageways for air between adjoining regenerators of side-by-side groups that are adapted for simultaneously conducting fuel gas and waste gases, respectively, said passageways being adapted to interrupt joints through which leakage may be induced from inflow to outflow regenerators by pressure differential therebetween and thereby prevent such leakage and communicably connected in series for flow of air through the passageways to regenerators operable for inflow of air simultaneously with operation of the adjacent fuel gas regenerator for inflow of fuel gas.

5. Coking retort oven structure comprising a series of combustion heating flues therefor, and means for supplying combustible media thereto, said means comprising a regenerator for conveying fuel gas, a regenerator for simultaneously conveying air adjoining the fuel gas regenerator on one side thereof, and a passageway for air on the other side of the fuel gas regenerator adapted to interrupt joints through which leakage may be induced from inflow to outflow regenerators by pressure differential therebetween and thereby prevent such leakage and communicating in series with the air regenerator and the atmosphere for air inflow through the passageway to the air regenerator and thence to the combustion flues in communication with the air regenerator during inflow of fuel gas through the fuel gas regenerator.

6. Coking retort oven structure comprising a series of combustion heating flues therefor, a series of side-by-side regenerators communicating therewith, said regenerators being in side-by-

side groups of two and the regenerators of certain of said groups being adapted for supplying air and fuel gas separately and simultaneously to said flues while other adjacent groups are adapted to conduct waste gases therefrom concurrently, and a passageway for conducting air between adjoining regenerators which are adapted to concurrently conduct fuel gas and waste gases, respectively, and thence to an air regenerator communicating in series with the passageway and operable for inflow of air simultaneously with the concurrent operation of said adjoining regenerators for conducting fuel gas and waste gas concurrently, whereby leakage between said adjoining regenerators is avoided.

7. Coking retort oven structure comprising a heating wall having a series of vertical combustion flues therefor, a series of side-by-side regenerators each of which extends parallel to said heating wall and communicating with said heating flues, said regenerators being operatively disposed in side-by-side groups each group comprising a pair of regenerators, and the side-by-side groups being operable in alternation with each other for concurrent inflow and outflow, passageways between adjoining regenerators of the side-by-side groups, and of vertical height substantially equal thereto, each of said passageways being communicably connected in series with a regenerator which constitutes one of the adjacent groups but which is not adjoining that passageway, for flow through the passageways of air between adjacent groups of regenerators and then into the regenerators in series with the passageways.

8. Coking retort oven structure comprising combustion chambers therefor, two rows of side-by-side parallel horizontally extending regenerators communicating therewith, a vertical dividing wall between said two rows and extending transversely of said regenerators, the regenerators of each row being operatively disposed in two sets for inflow preheating of gaseous combustion media and concurrent outflow of waste gases in alternation with each other, the regenerators of one set alternating position with those of the other set in the same row, passageways parallel to the regenerators of said rows and between regenerators of the two sets that adjoin each other side-by-side in said rows substantially coextensive in length and height with a regenerator that is contiguous thereto and communicating through ducts in said vertical wall with regenerators not adjoining passageways thus connected thereto.

9. Coke-oven structure comprising combustion chambers therefor, side-by-side groups of side-by-side regenerators communicating with said combustion chambers, the side-by-side groups being adapted for simultaneous inflow to and outflow from said combustion chambers in alternation with each other, each of said groups comprising a regenerator adapted to convey fuel gas during inflow operation, means providing spaces adapted to be filled with air on one side of each group between the fuel gas regenerator of the group and the next adjacent group of regenerators, each group also comprising a regenerator adapted to conduct air to the combustion chambers and communicating with said space of the group for inflow of air in series therfrom.

10. Coke-oven structure comprising heating walls therefor having vertical flame flues, side-by-side groups of side-by-side regenerators in series with said flame flues and adjacent groups

being adapted to operate in alternation with each other for concurrent inflow to and outflow from said flues, each of said groups comprising a regenerator adapted to convey fuel gas during inflow operation, and means comprising a regenerator for providing air spaces on opposite sides of the fuel gas regenerator of the group between the latter and the next adjacent group of regenerators to prevent leakage between the fuel gas regenerator and outflow regenerators, said last mentioned means communicating for flow of air from the space on one side to the air space on the opposite side of the fuel gas regenerators and thence to the vertical flame flues.

10 15. Coke-oven structure comprising a heating wall therefor having a series of vertical flame flues operatively disposed in two sets operable in alternation with each other for simultaneous inflow of combustion media and outflow of combustion products to and from each other, two sets of side-by-side regenerators communicating with said flame flues and adapted for alternate inflow to and concurrent outflow from said flues, certain of the regenerators of each set being adapted to convey fuel gas during inflow operation, the regenerators of said two sets of regenerators being disposed in side-by-side groups of alternating inflow and outflow groups, and each group when operable for inflow comprising at least one of said fuel gas regenerators and means comprising a regenerator for conveying air to the flame flues and a passageway in series therewith for feeding air to the regenerator for conveying air to the flame flues with the regenerators for air on one side and the passageways disposed on the opposite side of the fuel gas regenerators of the inflow groups so as to provide for air flow between fuel gas regenerators of the respective inflow groups and the next adjacent groups of outflow regenerators for preventing leakage between said fuel gas regenerators and said outflow regenerators.

20 25 30 35 40 45 50 16. A coke oven battery comprising a series of alternate horizontal oven chambers and heating walls therefor arranged side-by-side in a row, each of said heating walls being provided with vertical flame flues, said oven chambers and said heating walls extending transversely of the battery, regenerators side-by-side beneath and parallel to said oven chambers and said heating walls and communicating with said flame flues, said regenerators being in two rows laterally of each other and each row being of a width substantially half the width of the battery, and a vertical wall extending between said rows, the regenerators in each row being operatively disposed in two sets of groups with the groups of one set alternating in position side-by-side with those of the other set and operable in alternation with the groups of the other set for concurrent inflow and outflow, and each group comprising a regenerator and a parallel passageway substantially co-extensive therewith in length and height and communicating with said regenerator through a duct in said vertical wall and a second regenerator between said passageway and the first regenerator, and the second regenerator in each group being separated from the regenerator of the next group by said passageway, the second regenerator when operable for inflow being adapted to conduct fuel gas and the first regenerator and its passageway being adapted to conduct air separately and simultaneously.
